UNITED STATES PATENT OFFICE.

EMIL BENSON, OF HARTFORD, CONNECTICUT.

TROLLEY-RETRIEVER.

1,152,269.

Specification of Letters Patent. Patented Aug. 31, 1915.

Application filed August 15, 1914. Serial No. 856,964.

To all whom it may concern:

Be it known that I, EMIL BENSON, a citizen of the United States, residing at Hartford, in the county of Hartford and State of Connecticut, have invented certain new and useful Improvements in Trolley-Retrievers, of which the following is a specification.

This invention relates to trolley retrievers. 10 As the name implies such mechanism is intended for use in connection with the trolley pole of an electric car. Mechanism involving my invention is automatically operable to immediately draw a trolley pole that has 15 accidentally disengaged its wire to a position where it will not interfere with guy wires or supporting brackets.

The object of my invention is the provision of mechanism of this character that 20 will be simple and efficient in action, compact in size and the arrangement of its parts, and inexpensive to manufacture.

In the drawings accompanying and forming part of the present specification I have 25 shown in detail one convenient form of embodiment of the invention, which to enable those skilled in the art to practice the same will be set forth fully in the following description. The invention, however, is not 30 limited to this disclosure as changes may be made in many respects without departure from the scope thereof, as defined in the claims succeeding said description.

Referring to said drawings: Figure 1 is a 35 longitudinal sectional view of mechanism involving my invention. Fig. 2 is a transverse sectional view on line 2--2 of Fig. 1, looking in direction of the arrow. Fig. 3 is a transverse sectional view on line 3--3 of 40 Fig. 1, looking in direction of the arrow. Figs. 4 and 5 are detail views hereinafter more fully described.

Throughout the several views similar characters designate similar parts.

45 A suitable casing for inclosing the various parts of mechanism comprising my invention is designated by 2 and inasmuch as all the mechanism required is supported by said casing no difficulty is encountered 50 in attaching it to any suitable part of a car. To advantageously receive the trolley rope 3 it would ordinarily be secured to the dash.

One end of the casing 2 is closed by a plate or disk 4 having an inwardly extending stud 5 which as shown may be integral with said disk, the latter being firmly held in place by several screws 6. To receive the trolley rope 3 a reel 7 is mounted on the stud 5, said reel being hollow and having one side as 8 removable to permit the introduction of a 60 spring 9, (clock type) one end of which is fastened to stud 5 and the other end to a pin 10 extending transversely of the reel. The function of spring 9 is to exert a constant tendency to turn reel 7 in the direction of arrow A, thus maintaining a tension on the trolley rope while permitting the trolley pole to move up or down in conformity with varying levels of the trolley wire. A collar 11 secured at the free end of 70 stud 5 by a screw 12 prevents lateral movement of reel 7.

The mechanism thus far described is operable to take care of slack rope when the trolley is properly engaged with its wire. 75 Should it become disengaged it is desirable that instant automatic action be effected to draw the trolley pole to a level below the trolley wire. I provide mechanism, including an auxiliary spring, for accomplishing 80 this result and such mechanism will now be described. Axially aligned with the stud 5 is a shaft 13, extending at one end into a bore 14 in said stud 5 and supported at the other end by casing 2. Said shaft 13 loosely 85 carries a casing 15 provided for the auxiliary spring 16. The casing 15 is preferably formed in sections 17 and 18 which may be secured together by screws 19. To one of said screws 19 is attached the outer end 90 of spring 16, the inner end thereof being fastened to the shaft 13 by keys or studs 20. Contiguous to one side of spring casing 15 is a ratchet disk 21 keyed to shaft 13 and engageable by a pawl 22 pivoted as at 23 to 95 casing 2, and held to its work by a spring 24, all as clearly shown in Fig. 5. To prevent longitudinal movement of spring casing 15 a collar 25 is provided on shaft 13. Between this collar and the end of stud 5 is 100 mounted a clutch member 26, which is loose on shaft 13 but rotatively connected with the spring casing 15 by pins 27 and 28 which are tapped into the adjacent hub of said cas-

ing and extend into bores 29 and 30 respectively in said clutch member. Also by virtue of this construction the clutch member 26 may be shifted longitudinally as will 5 hereinafter appear to cause its teeth 31 to engage teeth 32 formed on the inner end of reel 7. Within the bores 29 and 30, are springs 33 and 34 respectively which constantly tend to force clutch member 26 into 10 engaged relation with reel 7. Normally, however, such engagement is prevented by a latch bolt or pin 35 mounted in a support 36 which is secured in casing 2 by screws as 15 37. One end of the latch pin is reduced as 20 at 38 to accommodate a spring 39 which normally tends to thrust said latch into locking position. To permit of the latch pin 35 being operated by hand as may be necessary in resetting the mechanism after it has been 25 tripped, it is provided outside the casing 2 with a manipulating ring 40. A stud 41 carried by latch pin 35 extends through a slot 42 in the support 36 and is provided at its free end with a roller 43 adapted to be 30 engaged by centrifugally operated levers hereinafter described.

The reduced inner end of latch pin 35 engages a groove 44 in clutch member 26, and as before stated holds said clutch in 35 disengaged relation. Also when in locking position (as shown) said pin 35 engages a shoulder 45 at one end of groove 44 and prevents rotation of clutch member 26 through the described connection of the latter with the spring casing 15. When spring 40 16 is placed under tension or wound up by means of the crank 47 it is maintained under tension by the pawl-and-ratchet engagement on one side and by engagement of clutch member 26 and locking pin 35 on the other. From the foregoing it will be apparent that if latch pin 35 be withdrawn, clutch member 26 will be instantly engaged with reel 7 and at the same time the rotative force of spring 16 will be released to 45 thereby drive reel 7 with sufficient power to pull the trolley pole down the desired amount.

Means for tripping latch pin 35 will now 50 be described. Such means include a pair of levers or arms 48 and 49 pivotally mounted on the inner side of reel 7, the pivot in each case being at one end of its respective arm so that upon rotation of reel 7 centrifugal 55 force will be developed in connection with said arms with a tendency to swing them outwardly. During comparatively slow rotation of reel 7 such as it would be subject to under normal conditions, it is, however, 60 essential to prevent said tendency of arms 48 and 49 to swing outwardly and I accomplish this satisfactorily by means of light springs as 50 and 51, which are held at one end in studs as 52 and 53 respectively and 65 pass freely through wire loops as 54 and 55

provided on the respective arms. In the event of the trolley pole, to which rope 3 is attached, becoming accidentally disengaged from its wire, the reel 7 will obviously be rapidly rotated and arms 48 and 49 will be 70 forced outwardly notwithstanding the tension of springs 50 and 51. While thus forced outwardly, arms 48 and 49 will engage roller 43 carried by stud 41, which as before stated is associated with the latch pin 35. The force of this engagement will be sufficient to trip latch pin 35 thereby releasing the mechanism as already described. After being tripped, resetting of the mechanism involves manual shifting of clutch 75 member 26 to a position where it will again be engaged by locking pin 35. For effecting this shifting of said clutch member I employ means including a shaft as 56, mounted in the support 36. The inner end 80 of said shaft carries a crank arm 57 having a stud 58 projecting therefrom and engaging groove 59 in clutch member 26. To the outer end of shaft 56 outside of the casing 2 is attached an operating lever 60. By 85 swinging this lever, clutch member 26 may be shifted as desired as will be clear from the showing in Fig. 4.

What I claim is:—

1. Mechanism of the character described 95 including in combination, a driven member, a reel, a clutch member rotatively associated with the driven member and shiftable to engage the reel, said clutch member having a peripheral groove terminating in a stop 100 wall, a locking bolt adapted to engage said groove to prevent both shifting and rotative movement of the clutch, and means operative by the reel for releasing said locking bolt.

2. Mechanism of the character described 105 including in combination, a driven member, a reel, a clutch member rotatively associated with the driven member and shiftable to engage the reel, said clutch member having 110 a peripheral groove ending in a stop wall and a continuous peripheral groove, a locking bolt normally in engagement with the peripheral groove having the stop wall, and a resetting device in engagement with the 115 continuous peripheral groove.

3. Mechanism of the character described 120 including in combination, a driven member, a reel, a clutch member interposed between the driven member and the reel, means for rotatively connecting the driven member with the clutch member, spring means within the clutch member for shifting said clutch member longitudinally into engagement 125 with the reel and a locking bolt for normally holding said clutch member against longitudinal shifting movement and also against rotative movement.

4. Mechanism of the character described 130 including in combination, a separable cas-

ing comprising two members, a shaft longitudinally fixed with respect to one of said members and supported by the other member which is freely removable therefrom, a driven member associated with said shaft, a reel wholly supported on the member which is freely removable from said shaft, and a clutch member supported on said

shaft, rotatively associated with the driven member, and shiftable to engage the reel. 10

In testimony whereof I affix my signature in presence of two witnesses.

EMIL BENSON.
